DESIGN.

—o—
C. WITTECK.

SPOON, &c.

No. 17,248.

Patented Apr. 5, 1887.

UNITED STATES PATENT OFFICE.

CHARLES WITTECK, OF NEW YORK, N. Y., ASSIGNOR TO WOOD & HUGHES,
OF SAME PLACE.

DESIGN FOR A SPOON, &c.

SPECIFICATION forming part of Design No. 17,248, dated April 5, 1887.

Application filed March 3, 1887. Serial No. 229,644. Term of patent 7 years.

To all whom it may concern:

Be it known that I, CHARLES WITTECK, of the city, county, and State of New York, have invented a new and Improved Design for 5 Spoons and other Table-Ware, of which the following is a full, clear, and exact description.

The leading feature of the design consists in an embossed shell-like leaf centrally at the 10 end of the handle, an embossed marginal scroll intersecting the leaf and extending along one edge in wave lines, and an irregular somewhat circular plain surface immediately below the shell-like leaf.

15 Centrally, at the end of the handle, an embossed figure representing a shell-like leaf, A, is produced, the stem of which leaf centering the curved end of the handle being covered by a circular scroll, B, in relief, which scroll 20 extends in relief in gradually-decreasing and wave-like lines along one side edge of the handle.

Upon the opposite side of the handle a leafed branch, C, is made to extend downward, 25 also in relief, the upper end parallel with the edge being connected with the shell-like central leaf, A. The other end of said branch, extending almost transversely the handle, terminates in a cluster of leaves, and above said 30 cluster the branch is provided with daisies or similar flowers in full bloom.

Centrally the enlarged end of the handle, immediately below the shell-like leaf A, an irregular plain flat surface, D, is produced, the 35 said leaf A engaging the top, the edge of a leaf upon the branch C one side, and one of the aforesaid flowers upon the branch a point

near the bottom. Intervening the other side of the plain surface D and the wave portion of the scroll B a more or less waving ribbon- 40 scroll, E, is produced, made to intersect the leaf A at one end and folded upon itself at the other.

Below the end of the branch C, where the handle narrows, a leaf ornament, F, is embossed, having a long stem extending downward and curled upon itself centrally the narrowest portion of the handle, and the stem of a small leaflet, G, of equal length to the stem of the leaf F, is made to engage in such manner as that the two stems form an ornamental contact. 45

I claim—

1. The design for spoons and other table-ware herein shown and described, the same 55 consisting of the shell-like leaf A, the intersecting circular and wave-like scroll B, the branch C, the irregular plain surface D between said branch and leaf, and the waving ribbon-scroll E, all arranged as set forth. 60

2. The design for spoons and other table-ware herein shown and described, the same 65 consisting of the shell-like leaf A, the intersecting circular and wave-like scroll B, the branch C, the irregular plain surface D between said branch and leaf, the waving ribbon - scroll E, and the oppositely - arranged leaf ornament F and leaflet G, all combined as herein set forth.

CHARLES WITTECK.
